UNITED STATES PATENT OFFICE.

EDWARD CECIL POULTNEY, OF LONDON, AND ARTHUR HEWITT GILLING AND HAROLD ARTHUR AKROYD, OF SHEFFIELD, ENGLAND.

STEAM LOCOMOTIVE.

Application filed November 7, 1925, Serial No. 67,621, and in Great Britain June 4, 1925.

This invention relates to steam locomotives of the articulated type comprising engine and tender units wherein the tender unit is equipped as a driving component complementary to the engine unit.

The chief object of the invention is to provide a locomotive which, for a given boiler capacity, will give a greater power without increasing the steam demand on the boiler, and, at the same time, provide a locomotive which is flexible so that it can negotiate curved tracks and operate over roads which require low axle loads.

Therefore, a locomotive embodying the invention is characterized in that the supply of steam to the cylinders of both the engine unit and the tender unit is cut off at a maximum of approximately 50 per cent of the piston-stroke.

A preferred embodiment of the invention is characterized in that the steam is cut off in the cylinders of the engine unit at a maximum of approximately 50 per cent of the piston-stroke, and the cylinders of the tender unit are of a less volume than the cylinders of the engine unit and are likewise operated on the same restricted or short cut-off system, the combined volume of the cylinders of the engine unit relatively to that of the cylinders of the tender unit being such that of the united tractive effort exerted by all the cylinders of both units the greater percentage is exerted by the cylinders of the engine unit.

In building a new locomotive in accordance with the invention, the cylinders of the engine unit are of increased volume as compared with a locomotive including existing standard practice; whilst, in applying the invention to an existing locomotive, the cylinders of the tender unit are of increased volume relatively to those adopted in a new locomotive.

A locomotive, embodying the invention as set forth, is further characterized in that the exhaust steam from the cylinders of the tender unit is wholly or partially utilized to pre-heat the feed water through the agency of a heater or heaters associated with the feed-water tank on the tender unit and the boiler on the engine unit.

A locomotive, embodying the invention as set forth, is still further characterized in

that the valves distributing the steam to the cylinders are, for purposes of starting, adapted to admit an auxiliary supply continuously for an amount of the pistons' stroke exceeding the restricted cut-off specified.

We will now describe, by way of example, one typical construction of a new locomotive incorporating the invention, and adapted to be worked with saturated or superheated steam at any desired pressure, and in so doing we will refer to the accompanying drawings whereof:

Fig. 1 is a diagrammatic side elevation of the complete locomotive; while

Fig. 2 is a plan thereof; and

Fig. 3 is an end elevation.

Fig. 4 is a fragmentary central vertical section of a steam distributing valve for the cylinders of the engine and tender units; while

Fig. 5 is a two-part transverse section thereof, with the upper half taken on the line Z—Z and the lower half on the line Y—Y; and

Fig. 6 is a fragmentary sectional plan on the line X—X in Fig. 4.

In this form, referring first to Figs. 1, 2 and 3, the engine and tender units, *a* and *b* respectively, are, stated generally, of the usual construction and assemblage, the engine unit *a* comprising the boiler *c*, the main driving cylinders *d*, the driving wheels *e* and the carrying wheels *f*; and the tender unit *b* including the customary fuel and water-carrying means *g* and *h* respectively, and the complementary driving cylinders *i*. The cylinders *d* and *i* are supplied with steam from the boiler *c* through the agency of suitable distributing valves.

As exemplified, the engine unit *a* is provided with two driving cylinders *d*, and the tender unit *b* with the same number of cylinders *i*, and in both cases they are of the "outside" arrangement. However, the number of cylinders *d* and *i* on the engine and tender units *a* and *b* may be various, and they may be of the "inside" arrangement, or partly of the "outside" and partly of the "inside"; there may, for instance, be two or more on both units, or there may be two or more on the engine unit and two on the tender unit. The cylinder connections may

be made to any axle or axles, as may be desired and convenient as will be evident from Fig. 1 which illustrates one appropriate plan. The cylinders *d* and *i* all operate on the restricted cut-off system, and, preferably, at a maximum rate of admission equal to 50 per cent or less of the piston-stroke. Appropriately, the combined cylinder volumes on the engine and tender units 10 *a* and *b* for a maximum cut-off of 50 per cent are, respectively, approximately 70 per cent and 30 per cent of the total.

The cylinders *d* on the engine unit *a* are or may be proportioned so that when working 15 on the restricted cut-off system they develop a rated tractive effort equal to cylinders working at an admission rate equal to approximately the full stroke, or say 90 per cent, which is the longest practicable admission period. When developing a given maximum rated tractive effort at a restricted cut-off, there is a steam-saving by volume or weight equal to the difference between the volume required for a given power output 20 by a given cylinder, working, at say, a 90 per cent cut-off, and, say, a 50 per cent cut-off, less the amount of extra steam required to fill the larger cylinder up to the point of cut-off; proportionately larger cylinders being required when the maximum admission rate is restricted so as to provide, for a given boiler pressure, a mean effective piston load equal to that obtained with smaller cylinders taking steam for full stroke. 25

The volume of steam saved by the use of this method of working is employed in the tender-unit cylinders *i* whose volume up to maximum cut-off is equal to the volume of the steam economized by the cylinders *d* of the engine unit *a*.

In this manner a greater amount of work is obtained by any given weight of steam furnished by any given boiler. Further, the additional power is transmitted for purposes of traction through the medium of the tender weight. Hence, for a given weight of the engine unit *a*, additional power is available without an increase in the weight of such unit.

Further, the number of coupled axles on the engine unit *a* need not be increased. The rigid wheel base is, therefore, not extended.

Assuming the maximum cut-off adopted 55 for the development of full power is 50 per cent of the stroke, then the steam used for a given rate of tractive power on the engine unit *a* will be

$$\frac{125.50}{100.90} = \frac{6250}{9000} = 0.69$$

or 69 per cent of that required, assuming 90 per cent cut-off is used and that the respective 50 per cent and 90 per cent cut-off cylinders have volumes in the ratio of 125;

100, i. e., the restricted cut-off cylinders being 25 per cent greater in volume to allow for the lower mean effective forward pressure due to the earlier cut-off. Then, for a restricted cut-off locomotive, the volume of 70 the cylinders *i* on the tender unit *b* is about 30 per cent up to the point of maximum cut-off of the total cylinder volume. Placing the smaller cylinders on the tender unit *b* corresponds to the lighter weight here available for adhesion. 75

In general, the adhesive weight on the engine unit *a* of the locomotive will be from 60 to 70 per cent of the total locomotive weight, leaving from 40 to 30 per cent available for adhesion on the tender unit *b*. 80

Thus, without introducing in any manner additional weight for adhesive purposes, by, as described, the proportioning of cylinders, and the utilizing of a maximum restricted 85 cut-off at the rate of say 50 per cent for all cylinders, the locomotive weight is made available for traction, and, at the same time, the power is distributed suitably throughout and proportional to the adhesive weights 90 available on the engine and tender units respectively, and, at the same time, a flexible locomotive is obtained.

Instead of proportioning the cylinders *d* of the engine unit *a* as described, the boiler pressure may be increased, the lesser-volume feature of the cylinders *i* of the tender unit *b*, however, being retained. 95

We have, in the foregoing, typified the cylinder volumes as being approximately 70 per cent and 30 per cent, but, manifestly, these proportions are subject to circumstances. For instance, in altering an old locomotive in accordance with the invention, the proportions may be typified by 64 per cent and 36 per cent. 100

The exhaust steam from the cylinders *i* on the tender unit *b* is used either wholly or in part to heat the feed water by means of a heater or a plurality of heaters *j*, and is not 110 returned to the engine unit *a* for exhaustion through the blast pipe. Appropriately, the heaters *j* are mounted on the tender unit *b*.

Two heaters *j* are exemplified in series, being interconnected by pipes *k* and *l*. They 115 are of the tubular type, the steam being adapted to be passed round the tubes, and the water passed through the tubes. The exhaust steam is led from the cylinders *i* by pipes *m* connected to a common pipe *n* which delivers it to one of the heaters *j*, whence it passes by the pipe *k* to the other heater *j*, and thence by way of a capped pipe *o* to the atmosphere. Through the agency of a steam pump *p*—there may, obviously, be 120 more than one—the water is drawn from the tank of the carrying means *h* therefor, delivered, forced through the heaters *j*, and then either returned to the tank *h*, or discharged into the boiler *c*. A pipe *q* constit- 125

tutes the pump suction, and the water is discharged into one of the heaters *j* by a pipe *r*, thence to the other heater *j* by pipe *l*, and is either returned heated to the tank *h* by pipes *s*, *t* and *u*, or is discharged into the boiler *c* on the "top feed" system by pipes *s*, *t*, *v* and *w*. The pipes *t*, *u* and *v* are associated with a multiple-way or by-pass valve *x* for directing the heated water to its required destination. Thus the tank *h* functions as a type of thermal storage.

The pump *p* is operated by steam generated in the boiler *c*, and is suitably connected by piping thereto or to an associated superheater, the exhaust being led by a pipe *y* and connection *z* to the common pipe *n* associated with the cylinders *i*. The pump *p* may be independently operated, and controlled at will by the engine men, or, by the provision of appropriate means, automatically put into action by the admission of steam to the cylinders *d* of the engine unit *a* on starting.

The pump *p* (or pumps) and the heaters *j* (or heater), arranged as described, will operate when the locomotive is moving with a predetermined steam pressure in the main steam pipes to the cylinders *d* and *i* or, in other words, any predetermined steam-chest pressure. Water will thus be drawn from the tender tank *h* and delivered to the heaters *j*, passing through them and returning to the tank *h*. When feed for the boiler *c* is required, water will be drawn from the tank *h* through the by-pass connection under the control of the valve *x* to suit the evaporation corresponding to the power output.

The feed heating will augment materially the steaming power of the boiler *c*, and, at the same time, increase the speed at which the locomotive will operate at its full power output.

The steam-distributing valves for the cylinders *d* and *i* may be of any appropriate type adaptable to furnish the auxiliary supply of steam already referred to for starting purposes. We, however, prefer a valve of the piston type which we have illustrated in Figs. 4, 5 and 6 to which we will now refer. According to our invention, we provide, at diametrically opposite points, a port 1 through each valve-head or piston 2 extending from the steam side and designed to communicate with the steam port 3 in the valve-liner 4 to constitute an auxiliary port for functioning in starting the locomotive. As a complement to this port 1, we cast or otherwise provide a bar 5 in the admission port 3 of the main valve. The arrangement of this auxiliary port 1, and of the corresponding bar 5, is such that when the main valve reaches the point of cut-off, the auxiliary port 1 is open for the maximum amount for the continuous supply of steam until at 80 per cent or thereabouts of

the piston-stroke it is cut off by the area of the auxiliary port being gradually decreased.

By this construction a relatively large auxiliary portway 1 may be used, thereby rapidly building up sufficient pressure to 70 start the locomotive when the main valve port 3 has been closed, yet, at the same time, due to the position of the auxiliary port 1 in relation to the bar 5 in the main port 3, the rapidly diminishing area of the steam-way through the auxiliary port 1 does not permit of an undue amount of steam entering the cylinder *d* or *i* after the main valve has cut off the steam. The economy obtainable by the restricted cut-off of the main 80 valve is in no way impaired by the auxiliary port 1; in fact, the normal area and form of the indicator diagram are not interfered with.

We have described the auxiliary port 1 85 and complementary bar 5 as of double structure, but they may be of single structure, or of multiple structure consisting of a plurality of ports 1 and bars 5 arranged ring-fashion or otherwise.

What we claim and desire to secure by Letters Patent is:

1. An articulated steam locomotive comprising, in combination, an engine unit; a tender unit; driving cylinders on the engine 95 unit; driving cylinders on the tender unit; said cylinders being complementary to the engine unit cylinders but of less volume than said cylinders; and means for cutting off the supply of steam to all the cylinders at a 100 maximum of approximately 50 per cent of the piston-stroke.

2. An articulated steam locomotive comprising, in combination, an engine unit; driving cylinders on the engine unit, the 105 steam being cut off therein at a maximum of approximately 50 per cent of the piston-stroke; a tender unit; and driving cylinders on the tender unit complementary to the cylinders on the engine unit and receiving 110 steam directly from the boiler, said tender-unit cylinders being of less volume than the cylinders of the engine unit, and being likewise operated on the same cut-off system of approximately 50 per cent of the piston- 115 stroke, and the combined volume of the cylinders of the engine unit relatively to that of the cylinders of the tender unit being such that of the united tractive effort exerted by all the cylinders of both units the greater 120 percentage is exerted by the cylinders of the engine unit.

3. An articulated steam locomotive comprising, in combination, an engine unit; driving cylinders on the engine unit, said cylinders, as compared with an engine embodying standard practice, being of increased volume, and the steam being cut off therein at a maximum of approximately 50 per cent of the piston-stroke; a tender unit; and driving 125

- 5 cylinders on the tender unit complementary to the cylinders on the engine unit and receiving steam directly from the boiler, said tender-unit cylinders being of less volume than the cylinders of the engine unit, and being likewise operated on the same cut-off system of approximately 50 per cent of the piston-stroke, and the combined volume of the cylinders of the engine unit relatively to 10 that of the cylinders of the tender unit being such that of the united tractive effort exerted by all the cylinders of both units the greater percentage is exerted by the cylinders of the engine unit.
- 15 4. An articulated steam locomotive comprising, in combination, an engine unit; a tender unit; driving cylinders on the engine unit; driving cylinders on the tender unit, said cylinders being complementary to the engine-unit cylinders but of less volume than said cylinders; means for cutting off the supply of steam to all the cylinders at a maximum approximating 50 per cent of the piston-stroke; and means for heating the boiler 20 feed-water through the agency of the exhaust steam from the cylinders of the tender unit.
- 25 5. An articulated steam locomotive comprising, in combination, an engine unit; a tender unit; driving cylinders on the engine unit; driving cylinders on the tender unit; said cylinders being complementary to the engine-unit cylinders but of less volume than said cylinders; means for cutting off the supply of steam to all the cylinders at a maximum approximating 50 per cent of the piston-stroke; and means for heating the boiler 30 feed-water through the agency of the exhaust steam from the cylinders of the tender unit.
- 35 6. An articulated steam locomotive comprising, in combination, an engine unit; a tender unit; driving cylinders on the engine unit; driving cylinders on the tender unit, said cylinders being complementary to the engine-unit cylinders but of less volume than said cylinders; means for cutting off the supply of steam to all the cylinders at a maximum approximating 50 per cent of the piston-stroke; and means for heating the boiler 40 feed-water through the agency of the exhaust steam from the cylinders of the tender unit, said means comprising a heater-organization associated with said cylinders, with the feed-water tank on the tender unit, and with the boiler on the engine unit.
- 45 7. An articulated steam locomotive comprising, in combination, an engine unit; a tender unit; driving cylinders on the engine unit; driving cylinders on the tender unit, said cylinders being complementary to the engine-unit cylinders but of less volume than said cylinders; means for cutting off the supply of steam to all the cylinders at a maximum approximating 50 per cent of the piston-stroke; and means for heating the boiler 50 feed-water through the agency of the exhaust steam from the cylinders of the tender unit, said means comprising a heater-organization associated with said cylinders, with the feed-water tank on the tender unit, and with the boiler on the engine unit, and adapted to convert the feed-water tank into a type of thermal storage by returning the heated feed-water thereto prior to delivering it to the boiler.
- 55 8. An articulated steam locomotive comprising, in combination, an engine unit; a tender unit; driving cylinders on the engine unit; driving cylinders on the tender unit, said cylinders being complementary to the engine-unit cylinders but of less volume than said cylinders; and means for cutting off the supply of steam to all the cylinders at a maximum of approximately 50 per cent of the piston-stroke, said means incorporating a distributing valve having expedients adapted to admit and control, for starting purposes, an auxiliary supply of steam continuously for an amount of the piston-stroke exceeding the specified cut-off.
- 60 9. An articulated steam locomotive comprising, in combination, an engine unit; a tender unit; driving cylinders on the engine unit, the steam being cut off therein at a maximum of approximately 50 per cent of the piston-stroke; a tender unit; and driving cylinders on the tender unit complementary to the cylinders on the engine unit and receiving steam directly from the boiler, said tender-unit cylinders being of less volume than the cylinders of the engine unit, and being likewise operated on the same cut-off system of approximately 50 per cent of the piston-stroke, and the combined volume of the cylinders of the engine unit relatively to 65 that of the cylinders of the tender unit being such that of the united tractive effort exerted by all the cylinders of both units the greater percentage is exerted by the cylinders of the engine unit, said percentage ranging from 64 to 70.
- 65 10. An articulated steam locomotive comprising, in combination, an engine unit; a tender unit; driving cylinders on the engine unit; driving cylinders on the tender unit, said cylinders being complementary to the engine-unit cylinders but of less volume than said cylinders; means for cutting off the supply of steam to all the cylinders at a maximum of approximately 50 per cent of the piston-stroke, said means incorporating a distributing valve having expedients adapted to admit and control, for starting purposes, an auxiliary supply of steam continuously for an amount of the piston-stroke exceeding the specified cut-off.

the piston-stroke, said means incorporating a distributing valve having expedients adapted to admit and control, for starting purposes, an auxiliary supply of steam continuously for an amount of the piston-stroke exceeding the specified cut-off; and means for heating the boiler feed-water

through the agency of the exhaust steam from the cylinders of the tender unit.

In testimony whereof, we affix our signatures. 10
